GROUND CONNECTION

Filed June 14, 1928

By *Harry Leesey*, Attorney

UNITED STATES PATENT OFFICE.

GEORGE E. ALLEN, OF BUFFALO, NEW YORK.

GROUND CONNECTION.

Application filed June 14, 1928. Serial No. 285,343.

In the grounding of electric circuits a damp connection is superior and preferable to a dry connection. Therefore the present invention aims to provide means whereby a ground connection may be maintained in a damp condition so as to obtain the best possible results, particularly in the grounding of radio frequency circuits.

While the drawing illustrates a preferred embodiment of the invention, it is to be understood that in adapting the means to meet specific needs and requirements, the design may be varied and such other changes in the minor details of the invention as claimed, without departing from the spirit thereof.

For a full understanding of the invention and the merits thereof, reference is to be had to the following description and the drawing hereto attached, in which:

20 Figure 1 is an elevational view of a grounding strip of sheet metal having marginal portions separated by inclined cuts.

25 Figure 2 is a sectional view of the device, the grounding strip being disposed to present its edge.

Figure 3 is a horizontal sectional view on the line 3—3 of Figure 2.

30 Figure 4 is a detail view of portion of the device and the clamp whereby it may be attached to a water pipe.

Figure 5 is an end view of the clamp as applied to a water pipe, the latter being in section.

35 Corresponding and like parts are referred to in the following description and designated in the several views of the drawing by like reference characters.

The numeral 1 denotes a strip of sheet metal which may be of any length and width.

40 An end portion of the sheet metal strip 1 is reduced as indicated at 2 to provide a projecting part for the attachment thereto of the wire to be grounded.

45 Slits or cuts 3 are formed in opposite marginal edges of the strip 1 and incline inwardly and downwardly from the edges of the strip. In the preferable arrangement the slits or cuts in opposite edge portions of the strip coincide and are reversely inclined.

50 The parts separated by the inclined cuts 3 form tongues 4 which are bent laterally, the tongues along one edge being bent in the same direction and opposite to the tongues along the other edge of the strip. The strip

55 thus formed presents the appearance substantially as shown in Figures 2 and 3 and is

pressed into a tube 5 of suitable length and diameter. The pointed ends of the tongues 4 positively engage the inner wall of the tube 5 thereby assuring an electric connection. 60 The number of tongues 4 results in the provision of a plurality of contacts thereby assuring positive electrical connection between the strip 1 and tube or casing 5. Suitable closures are fitted to the ends of the tube or 65 casing 5 to prevent loss of water supplied thereto by evaporation or otherwise. A plate 6 is shown as closing one end of the tube and an opening is formed therein in which is fitted a plug 7. A suitable fitting 8 is applied 70 to the opposite or lower ends of the tube 5 and may be connected to a water pipe or fixture in any determinate way.

When the grounding strip 1 is properly positioned within the tube or casing 5 the 75 latter is supplied with water and is closed. The projecting end portion 2 of the strip is adapted to have the wire to be grounded connected thereto in any manner.

For connecting the device to a water pipe 80 a clamp has been devised and comprises similar parts 9 and 10 which are shaped to fit about a pipe 11 as indicated most clearly in Figure 5 of the drawing. The gripping faces of the members comprising the clamp are 85 toothed or serrated to prevent slipping. Apertured ears 12 project from opposite longitudinal edges of the parts comprising the clamp and receive bolts 13 by means of which the clamp is secured upon the pipe 11 in the 90 desired position. One of the members of the clamp as 10 is formed with the projection 14 in which is formed a threaded socket to receive the threaded end of the fitting 8 as shown most clearly in Figure 4 of the 95 drawing. When connecting the device to a radiator or other fixture a suitable fitting may be coupled to the part 8 to admit of the device occupying a vertical position when connected to the fixture or part to which it 100 is applied.

A bolt 15 and cooperating nut and washer are shown as means for connecting the wire to be grounded to the projecting end 2 of the strip 1. 105

Having thus described the invention, I claim:

1. An electric grounding device comprising a metal strip provided along opposite edges with tongues which form contact elements. 110

2. An electric grounding device including

- a metal strip having portions partly severed from opposite edges and bent laterally in opposite directions to provide a plurality of contacts. 20
5. 3. An electric grounding device including a sheet metal strip having inwardly extending cuts along its marginal edges and having the portions separated by the cuts bent laterally to provide a plurality of contact points. 25
10. 4. An electric grounding device including a casing adapted to contain water and a strip therein immersed in the water and provided with a plurality of points electrically connected with the inner wall of the casing. 30
15. 5. An electric grounding device comprising a closed casing and a grounding member therein provided with a plurality of points electrically engaging the inner wall of the casing the latter adapted to receive water to insure a damp connection. 35
6. An electric grounding device comprising a casing adapted to contain water, a grounding member therein immersed in the water and provided with a plurality of points electrically connected with the casing. 40
7. An electric grounding device comprising a casing adapted to contain water a grounding member therein and a clamp for connecting the casing to the water pipe such clamp comprising complementary members having off standing apertured elements to receive connecting bolts and one of the clamp members having a projection to which the casing is fitted. 45

In testimony whereof I affix my signature.
GEORGE E. ALLEN. [L.S.]
